UNITED STATES PATENT OFFICE

ALFRED C. GUNSAULUS, OF AKRON, OHIO

DESIGN FOR A TIRE

Application filed July 28, 1931. Serial No. 40,703. Term of patent 14 years.

To all whom it may concern:

Be it known that I, ALFRED C. GUNSAULUS, a citizen of the United States, residing at Akron, in the county of Summit and State of Ohio, have invented a new, original, and ornamental Design for a Tire, of which the following is a specification, reference being had to the accompanying drawings, forming part thereof.

Fig. 1 is a perspective view of a pneumatic

tire having a tread design embodying my invention shown thereon; and

Fig. 2 is a cross-sectional view taken substantially along the line II—II of Fig. 1.

Fig. 3 is a plan view of a portion of the tire; and

Fig. 4 is a side elevation thereof.

I claim:

The ornamental design for a tire, as shown.

ALFRED C. GUNSAULUS.
